UNITED STATES PATENT OFFICE.

LEWIS W. EGGLESTON, OF WHEATON, ILLINOIS, ASSIGNOR TO AMERICAN RADIATOR COMPANY, OF CHICAGO, ILLINOIS, A CORPORATION OF NEW JERSEY.

STEAM-RADIATOR.

1,104,350.

Specification of Letters Patent. Patented July 21, 1914.

Application filed July 21, 1913. Serial No. 780,163.

To all whom it may concern:

Be it known that I, LEWIS W. EGGLESTON, a citizen of the United States, residing at Wheaton, in the county of DuPage and State 5 of Illinois, have invented new and useful Improvements in Steam-Radiators, of which the following is a specification.

My invention relates to certain new and useful improvements in steam radiators and 10 is fully described and explained in the specification and shown in the accompanying drawings, in which—

Figure 1 is an elevation of part of a system including a radiator embodying my improvements; Fig. 2 is a section on the line 2 of Fig. 1; Fig. 3 is a section on the line 3 of Fig. 1; Fig. 4 is a section on the line 4 4 of Fig. 3, and Fig. 5 is a section on the line 5 5 of Fig. 3.

Referring to the drawings, 6 are the ordinary heating sections of a steam radiator supplied by a pipe 7. Between the supply pipe and the sections 6 is a humidifying device. This has a steam loop 8 generally similar to those used in an ordinary steam radiator. The space within the loop 8 is, however, inclosed to form a chamber 9 to which water is supplied by a pipe 10. The chamber 9 is provided with an outlet-opening 11 at its upper end, this opening preferably being on the side toward the steam sections of the radiator, so that steam issuing from the humidifying device will enter the interstices of the radiator thereby humidifying the hot 35 and otherwise dry air between the sections thereof.

For the purpose of making the humidifying device automatic in its operation, the pipe 10 is connected to a tank 12 in which 40 the water-level is maintained constant by means of a float-valve 13 of ordinary form. The constant level tank 12 may, and preferably does, supply humidifying devices on all the radiators on a given floor in an obvious manner.

14 is a valve interposed in the pipe 10, this valve being of the type which is opened and closed by electrical means, and 15 is a hygrometer adapted to open and close the 50 circuit controlling the valve 14. While there are various devices available for this purpose and it may be suggested that for ordinary residence, or office, use, where the

temperature is maintained constant, or substantially so, any wet bulb thermometer provided with proper electrical contacts may be used to control the circuit.

I am aware that it has heretofore been proposed to cause the steam within a radiator to vaporize water for humidifying purposes. As a rule, however, such efforts have been made in rather tall receptacles. I have discovered that the reason why such devices are generally unsuccessful is that they expose to the chilling effects of the air a considerable area of the walls of the water-containing vessel above the water-level therein. As a result the water may boil briskly at the bottom of one of the receptacles, only to condense in the upper part, so that only a small proportion of the water vaporized actually passes out into the room. This difficulty has been remedied in the present device by carrying the steam-section entirely around the water receptacle and as well making 75 the water-receptacle pointed in cross-section at its front and back edges, the steam section being so shaped as to lap around the water receptacle as best shown in Fig. 2. By this means the entire water-receptacle is maintained at such temperature that there is practically no condensation in its upper part and the steam issues rapidly from the outlet 11. I have tried devices in which the steam entirely surrounds not only at top, 80 bottom and edges, but as well on both faces, and under certain conditions such practice might be desirable. However I have found that the water may then boil so violently as to issue in liquid form from the outlet 90 pipe, and I have therefore arrived at substantially the cross-section shown in Fig. 2, as the most desirable. In this form the steam space sufficiently surrounds the water receptacle to prevent condensation in the 95 upper part thereof but still there is no such excessive heat as will cause the water to boil violently and throw itself out in liquid form. With a device of this character applied to each radiator in a building, it is very easy 100 indeed to vaporize enough water to keep the humidity at a very comfortable point.

I am aware that considerable variation is possible in the details of the present construction without departing from the spirit 105 thereof, and I do not therefore intend to

limit myself thereto, except as pointed out in the following claims, in which my intention is to claim all the novelty inherent in the construction as broadly as is permitted by the state of the art.

What I claim as new and desire to secure by Letters Patent, is:

1. A steam radiator comprising, in combination, steam sections, one of said sections being provided with a water receptacle in the interior thereof, the said water receptacle being provided adjacent its upper end with a vapor outlet adapted to discharge vapor through the interstices of the radiator.

2. A steam radiator comprising, in combination, steam sections, a vaporizing section in series therewith, a water receptacle within said vaporizing section and in the plane thereof and wholly surrounded thereby on its bottom, top and both edges to receive heat therefrom, the said water receptacle being provided adjacent its upper end with a vapor outlet opening adapted to discharge vapor through the interstices of the radiator.

3. A steam radiator comprising, in combination, steam sections, a vaporizing section in series therewith and provided in its interior with a water receptacle in the plane thereof and surrounded thereby on its top, bottom and both edges, said vaporizing sec-

tion partially overlapping the faces of said receptacle to heat the same.

4. A steam radiator comprising, in combination, with steam sections, a vaporizing section in series therewith, with a water receptacle in the interior thereof and in the same plane therewith to receive heat therefrom, and means to supply water to said receptacle.

5. A steam radiator comprising, in combination, steam sections, a vaporizing section in series therewith, a water receptacle wholly within said vaporizing section and in the plane thereof, to receive heat therefrom, and means controlled by the humidity of the apartment for supplying water to said receptacle.

6. A steam radiator comprising, in combination, steam sections, a vaporizing section in series therewith, a water receptacle wholly within said vaporizing section and in the plane thereof and surrounded thereby on its top, bottom and both edges, said receptacle having an outlet positioned to discharge vapor into the interstices of the steam sections, for the purpose set forth.

In testimony whereof I have hereunto set my hand this 1st day of July, 1913.

LEWIS W. EGGLESTON.
